(57) **CLAIM**

The ornamental design for a dry erase display unit, as shown and described.

DESCRIPTION

FIG. 1 is a front perspective view of the dry erase display unit showing my new design. The broken lines showing a pen at the left of the dry erase display unit and an article in the interior of the dry erase display unit are for illustrative purposes only and form no part of the claimed design; FIG. 2 is a rear perspective view of the dry erase display unit of FIG. 1;

FIG. 3 is a left side elevational view of the dry erase display unit of FIG. 1;

FIG. 4 is a front elevational view of the dry erase display unit of FIG. 1;

FIG. 5 is a right side elevational view of the dry erase display unit of FIG. 1;

FIG. 6 is a rear elevational view of the dry erase display unit of FIG. 1;

FIG. 7 is a top plan view of the dry erase display unit of FIG. 1;

FIG. 8 is a bottom plan view of the dry erase display unit of FIG. 1;

FIG. 9 is a rear perspective view of the dry erase display unit of FIG. 1 in a closed configuration;

FIG. 10 is a front perspective view of the dry erase display unit of FIG. 1 in a configuration in which a sliding tab has been extended;

FIG. 11 is a front perspective view of the dry erase display unit of FIG. 1 showing the insertion/removal of an article in the interior of the dry erase display unit; and,

FIG. 12 is a front perspective view of the dry erase display unit of FIG. 1 in a configuration without sliding tabs.
